UNITED STATES PATENT OFFICE.

PETER M. KLING, OF ELIZABETH, NEW JERSEY.

CAR-BRAKE.

No. 830,154.

Specification of Letters Patent.

Patented Sept. 4, 1906.

Application filed August 21, 1905. Serial No. 275,106.

To all whom it may concern:

Be it known that I, PETER M. KLING, a citizen of the United States, residing at Elizabeth, in the county of Union and State of New Jersey, have invented certain new and useful Improvements in Car-Brakes, of which the following is a specification.

My present invention relates to improvements in brake mechanism, and has for its object to provide an improved mechanism for transmitting power from the crank-shaft to the brake beam or lever in a brake mechanism.

More particularly described, my invention has for its object to provide a power-transmitting means for brake mechanism especially adapted for high-speed railway-cars having end platforms which are below the level of the floor or the main or central part thereof.

In high-speed railway-cars it is often essential that the main portion of the floor-frame—that is, that portion over the car-trucks—be elevated to give sufficient space for the trucks, the end platforms being nearer the rails to provide steps up to said floor. It is also advisable that the brake-chains be on a plane above the trucks. For this reason I have provided a means whereby the brake-chains may be mounted immediately beneath the central or raised portion of the floor and above the trucks.

I provide by the present invention several forms of mechanism whereby the brake-chains may be actuated by well-known forms of brake-controlling mechanism.

In detail, my invention consists in the provision of a brake-chain-winding spindle and several forms of mechanism for actuating said spindle, whereby power may be transmitted from a controlling device on one plane of action to the brake chains or rods on another plane of action. Such an arrangement is especially advantageous in the case of high-speed cars in which the floor or the central portion thereof is elevated above the end platforms and where it is desired to control the brake by hand-operated cranks on the end platforms. In such case the power is to be transmitted from one end of the crank-shaft or other spindle on one plane of action to the brake-chains on a different plane of action through the medium of the interposed brake-chain-winding spindle.

A further object of my invention is to pro-

vide improved details of structure herein described, and shown in the accompanying drawings, in which like reference characters refer to like parts, and in which—

Figure 1 is a general sectional side elevation of my improved car-brake. Fig. 2 is a detail perspective view of the two-part supporting-bracket for the brake-chain-winding spindle, showing the parts in correlative assembled positions. Fig. 3 is a like view of the adjusting member of said bracket. Fig. 4 is a view like Fig. 1 of an improved slack-take-up device forming a part of my invention. Fig. 5 is a view like Fig. 2 of the supporting-bracket with such device attached. Fig. 6 is a general sectional side elevation of my improved car-brake, showing slight modifications of structure. Fig. 7 is a like view showing other modifications of structure, and Fig. 8 is a similar view showing means for operating the spindle by air.

Referring now in detail to the drawings, 1 represents the main or raised portion of the floor of a high-speed railway-car; 2, one of the end platforms of the same; 3, the car-truck; 4, the crank-shaft of the brake-controlling mechanism—such as shown and described in my Letters Patent No. 781,533, dated January 31, 1905, entitled "Brake mechanism"—and 5 a shaft adapted to be actuated by the crank-shaft 4 by mechanism within the housing 6 clearly shown and described in the said patent, so that said shaft 5 will at the commencement of the braking mechanism be rapidly rotated to take up the slack in the brake-chain and at the completion of the braking operation will be more slowly rotated, but with increased power. I do not describe in detail the structure within the housing 6, since this is not an essential feature of my invention, as any means may be employed for rotating the shaft 5—as, for instance, the shaft 5 may be the lower end of the crank-shaft 4. The shaft 5 therefore is rotated in any suitable manner and has mounted at its lower end a sprocket 6, connected by an endless chain to the sprocket 8, mounted on a spindle 9, rotatably mounted in lugs 10 11 on bracket 12.

Near the upper end of the spindle 9 is secured one end of the brake-chain 13, which chain is connected in the customary manner to the brake beam, lever, or other mechanism for applying the shoes, which is not herein shown. Since the brake-beams (not shown)

or other shoe-applying devices are located on the car-truck and extend upwardly to a point above the truck and immediately beneath the car-floor, it is essential that the 5 brake-chain 13 be mounted to exert its pull on substantially the same plane as the brake beam and lever or other shoe-applying device. The spindle 9 therefore forms means of transmitting power to the brake-chain in 10 substantially the same horizontal plane with the brake-beam or the like from a point on the same horizontal plane with the lower end of the crank-shaft or other shaft operated by the brake-controller, Figs. 1 and 2.

15 In different cars the floor is at different heights above the level of the end platforms. Hence it becomes necessary to provide a universal form of bracket 12, which can be adjusted to different levels on the car-frame, so 20 as to elevate or lower the winding end of the brake-chain 13 and the spindle 9. For this purpose I have constructed the bracket 12 in two parts—the main or spindle-carrying member 12 and the adjustable clamping member 12^a.

25 The main member 12 is provided with serrations or teeth 14, adapted to engage the serrations or teeth 15 on the adjustable or clamping member 12^a, the two members being secured together against 30 movement by the nut 16 and bolt 17, said bolt 17 being adjustable in a slot 18 in the member 12. Member 12 is also provided with suitable bolt-eyes 19, through means of which the same may be secured to the frame by means of bolts 20, passing through a beam 35 in the floor-frame. The said member 12 fits snugly against one face of a beam in the floor-frame, here shown as the door-sill, and the adjustable or clamping member 12^a fits snugly 40 against the under side of said beam and is secured thereto by means of spikes or other medium 21, inserted through the eyes 22.

It will probably be necessary that some adjustable slack-take-up means be used in connection with my improved mechanism, and 45 for this purpose I have shown in Figs. 4 and 5 such an arrangement. Therein I form the main member of the bracket 12 of several parts 12^b and 12^c. The part 12^b is adapted 50 to be secured to the framing of the car and engages the adjustable clamping member 12^a. The parts 12^c are spindle-supporting arms adjustable horizontally on arms 12^d of part 12^b through medium of serrations or teeth 12^e and bolts 12^f in slots 12^g. This forms 55 merely one of many examples of the manner of obtaining a horizontal as well as a vertical adjustment of the spindle 9.

In Fig. 6 I have shown a slight modification in the form of mechanism thus far described, wherein one device of a mechanism for rapidly applying the brake is mounted on the crank-shaft 23, and the other device of such mechanism is mounted on a spindle 24. 60 Such members consist of a pair of inverted

cones 25 26, the base of the cone 25, which is mounted on the crank-shaft 23, being uppermost, and the apex of the cone 26, which is mounted on the spindle 24, being uppermost. 65 70 75 80 85 90 95 100 105 110 115 120 125 130 cones 25 26, the base of the cone 25, which is mounted on the crank-shaft 23, being uppermost, and the apex of the cone 26, which is mounted on the spindle 24, being uppermost. 27 is an operating-cable connected to the bases of the respective cones, so that when the cable 27 fills one of the cones the opposite cone is empty. Through use of this mechanism at the commencement of the braking operation the rotation of the crank-shaft 23 will be relatively slow and the rotation of the spindle 24 relatively fast, so that the slack in the brake-chain 28 will be rapidly taken up. At the completion of the braking operation after the slack in the chain 28 is taken up and the 80 85 90 95 100 105 110 115 120 125 130 135 140 145 150 155 160 165 170 175 180 185 190 195 198 200 205 Having thus described my invention, the following is what I claim as new therein and desire to secure by Letters Patent—

1. In a brake mechanism, the combination with a brake-controlling device and a brake-cable; of a winding-spindle mounted at a distance from said controlling device and connected to said brake-cable on one plane of action, and suitable gearing between said controlling device and said spindle on a different plane of action. 50
2. In a brake mechanism, the combination with a controlling device at one end of the car, and a brake-cable; of a spindle centrally located on said car and connected to said brake-cable, and suitable gearing between said controlling device and said spindle. 55
3. In a brake mechanism, the combination with a controller and a brake-cable, of a winding device suitably geared to said controlling device on one plane of action and connected to said brake-cable on a higher plane of action. 60
4. In a brake mechanism, the combination with a controller, located at the end of the car and a brake-cable; of a vertical winding device mounted beneath the floor and connected to said brake-cable in one horizontal plane, and suitable gearing between said controller and said winding device on a different horizontal plane. 70
5. In a brake mechanism, the combination with a controller, and a brake-cable; of a winding device geared to said controller and connected to said brake-cable and adapted to transmit power from said controller on one plane of action to said brake-cable on a higher plane of action. 75
6. In a brake mechanism, the combination with a controller and a brake-cable; of a winding device geared to said controller and connected to said brake-cable and adapted to transmit power from said controller on one plane of action to said brake-cable on another plane of action, and an adjustable bracket for supporting said winding device. 80
7. In a brake mechanism, the combination with a controller and a brake-cable; of a winding device connected to said cable and geared to said controller and an adjustable bracket for supporting said winding device comprising a main or supporting member and an adjustable or clamping member. 85
8. In a brake mechanism, the combination with a controller and a brake-cable; of a winding device for operating said cable, a bracket for supporting said winding device and adapted to be secured to the car-frame beneath the platform, and suitable connection between the controller and the winding device for operating the latter by the former. 90
9. In a brake mechanism, the combination with a brake-cable; of a winding device connected to said cable on one plane of action, and means for operating said winding device connected thereto on a lower plane of action. 95
10. In a brake mechanism, the combination with a brake-cable on one plane of action, means for controlling said cable located on a lower plane of action, and suitable operating connection between said controlling means and said cable. 100
11. In a brake mechanism, the combination with a controller; of a brake-cable mounted on one plane of action, and means for transmitting power from said controller at a point on a lower plane of action to said brake-cable. 105
12. In a brake mechanism, the combination with a brake-cable, a vertical spindle centrally located on the car-frame for operating said cable, and means for operating said spindle. 110
13. In a brake mechanism, the combination with a controller, of a brake-cable on one plane of action, and variable-speed gearing on a lower plane of action, transmitting power from said controller to said cable. 115

PETER M. KLING.
